UNITED STATES PATENT OFFICE.

WILLARD C. RICHARDSON, OF SAUGUS, MASSACHUSETTS.

SHOE FORM.

Application filed March 19, 1925. Serial No. 16,735.

My invention relates to shoe forms and has particular reference to a type I have now perfected, having a high finish covering commonly of celluloid or other suitable sheet material.

In use, the tendency of such covering is to sever its adhesion starting at the edges and pulling away from the foundation, usually at the curved portions, this feature being termed "bridging". A further tendency of the covering is to spread the form at its ball portion to an extent detrimental to its usefulness, so that, while with forms as heretofore made it was essential merely to furnish an inner support guarding against collapse from outer pressure, as provided in my Letters Patent, Serial Number 898,137, it now becomes necessary to supply a flexible holding brace sufficient to avoid spreading of the form at the ball portion, yet adequately resisting outer pressure. Flexibility is required that the form while in use may tightly fit in shoes of slight manufacturing variation. Adjustability of the holding brace is also required that the form may be utilized for shoes of varying standard widths. In attaching braces, it has heretofore been necessary but time consuming and difficult, to place the rivets or other fastenings by which the brace is held to the form into and through a hole previously placed in the brace for this purpose. All of which has added materially to the cost of manufacture.

The objects of my invention are to furnish the stated requirements and overcome the stated difficulties and tendencies; to reinforce the ball portion of the form at the points where the holding brace is attached; to provide an improved method of manufacture; and to provide the various other advantages and results made evident from the following specification.

I accomplish the objects of my invention by forming a shoe form foundation from wet sheet material by fitting the same over an ordinary last, lasting the same in position thereon, allowing the said material to dry on said last, thereafter trimming said foundation about the bottom edge so as to free the sheet material from the last about which it is shaped, then dipping the foundation in a hardening solution, then covering said foundation with sheet celluloid, first made pliable in a solution of alcohol, tightly shaping and fitting said celluloid about said form foundation so that it contacts at all points

and hooking the edges thereof about the edges of said foundation, then allowing the celluloid to harden. Next securing to the sides of the ball portion of the covered form, 60 an adjustable bridge of slightly tempered material by fastening means which clamp the form foundation and the finishing cover thereon at overlapping points. It will be readily seen that the overlapping of the 65 foundation by the finishing cover at the ball portion furnishes a triple ply to which the adjustable bridge is attached, thus affording a complete and efficient reinforcement, guarding against the bridge breaking away 70 from its fastenings.

Referring to the accompanying drawings which form a part of this specification, Figure 1 is a side view of a shoe form with a section removed to show my improved brace 75 in position. Figure 2 is a bottom view thereof. Figure 3 is a cross sectional view of the form on the line A—A in Figure 2. Figure 4 is a perspective view showing the detail construction of my improved brace. 80 In Figures 1, 2 and 3, B shows the inner foundation. C is the finishing cover applied to the foundation B and hooked up around the edges as shown at D in Figure 3. H shows the rivets by means of which the 85 supporting brace is secured to the form. In Figure 4, E shows anchor sections secured to the brace F by the rivets G. H¹ shows the relative position where the rivets H pierce the anchor sections E. This position 90 is varied at the will and convenience of the operator or manufacturing requirements.

While any suitable manufacturing materials may be employed, I prefer to utilize flat pieces of fiber board for the form foundation, celluloid for the finishing covering, slightly tempered steel for the holding brace, and fiber board for the anchor sections. It is evident that the anchor sections must be formed from easily penetrable material in 100 order to avail the manufacturing benefits resulting from their use, that the rivets H may be blindly placed without necessity of fitting the same into and through a prepared orifice.

The assembled brace as shown in Figure 4 is conveniently manufactured during quiet periods in the industry and kept ready for instant use and convenient application to the forms as such forms come through the plant 110 on order. The use of a machine in placing the rivets H vastly reduces time and expense

in manufacture, this being made possible by the use of the anchor sections as described. The fastening of the adjustable bridge at a three ply point and hooking of the finishing cover about the edge of the foundation permanently holds the cover firmly in place throughout the life of the form, eliminating all tendency to sever its adhesion and bridge.

The width of the form at its ball portion 10 is varied by spreading or closing the brace, this being accomplished by bending at F^1 (see Figure 4), the spring temper being adaptable for such adjustment. In this connection it will be observed that the arch 15 formed by the bend at F^1 is comparatively small and is remote from the inner sides and top of the shoe form, being centered in the bottom opening of the form and between the lower side edges of the latter whereby it is 20 free to flex inwardly and outwardly for closing and spreading the brace.

Having thus described my invention I claim as new and desire to secure by Letters Patent of the United States of America:

25 1. A shoe form having a foundation of sheet material and a finishing cover attached thereto, said cover being hooked about the edges of said foundation to preserve its adhesion thereto, in combination with an adjustable spring bridge spanning the ball portion of said form, the respective ends thereof being secured to the sides of said ball portion by fastening means which clamp and hold the form foundation, and finish- 30
35 ing cover thereon.

2. A spring bridge for a shoe form comprising a pair of anchor sections respectively formed of a flat piece of fiber board, and a connecting spring of slightly tempered steel having its ends secured to the said anchor 40 sections and having its intermediate portion extending in an arch between the said sections.

3. A flexible holding brace for the ball portion of a shoe form consisting of a strip 45 of metal having secured to its ends separately formed anchor sections for attaching the brace to the sides of the form, said anchor sections being formed of easily penetrable material through which the attaching 50 means may be blindly placed without the necessity of fitting the same into and through a prepared orifice and said strip being of a spring temper adapting it to be bent for spreading or closing the brace to vary the 55 width of the form at its ball portion.

4. In combination, a shoe form having a bottom opening, and a spring brace spanning the said bottom opening at the ball portion of the said form and having anchor 60 sections riveted to the form to secure the said brace thereto, said anchor sections and said shoe form being respectively composed of easily penetrable material to enable the holding rivets to be blindly placed so that the 65 position of the anchor sections with respect to the form can be varied.

In testimony whereof I affix my signature.

WILLARD C. RICHARDSON.
